US0D1029830S

(12) **United States Design Patent** (10) Patent No.: **US D1,029,830 S**
(45) Date of Patent: ** Jun. 4, 2024

(54) **APPARATUS FOR RECORDING,
TRANSMITTING OR PROCESSING
INFORMATION**

(71) Applicant: **Siemens Aktiengesellschaft**, Munich (DE)

(72) Inventors: **Chang Sen Chen**, Chengdu (CN); **Wei Zhang**, Sichuan (CN); **Ming Zhao**, Sichuan (CN)

(73) Assignee: **SIEMENS AKTIENGESELLSCHAFT**, Munich (DE)

(**) Term: **15 Years**

(21) Appl. No.: **29/828,090**

(22) Filed: **Feb. 24, 2022**

(30) **Foreign Application Priority Data**

Aug. 27, 2021 (CN) 202130563696.X

(57) **CLAIM**

The ornamental design for an apparatus for recording, transmitting or processing information, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof;

FIG. 7 is a front, top and left-side perspective view thereof; and,

FIG. 8 is a front, bottom and right-side perspective view thereof.

The broken lines in the drawings depict portions of the apparatus for recording, transmission or processing information that form no part of the claimed design.

1 Claim, 8 Drawing Sheets
